Primary Examiner — Mary Ann Calabrese*Assistant Examiner* — Catherine Ho(74) *Attorney, Agent, or Firm* — Brad Bertoglio; Intelink Law Group, P.C.(57) **CLAIM**

The ornamental design for an interactive multimedia table, as shown and described.

DESCRIPTION

FIG. 1 is a top perspective view, showing my new design; FIG. 2 is a front elevation view thereof, the rear elevation view being a mirror image thereof;

FIG. 3 is a left elevation view thereof, the right elevation view being a mirror image thereof;

FIG. 4 is a top plan view thereof; and,

FIG. 5 is a bottom plan view thereof.

Portions of the interactive multimedia table shown in broken lines form no part of the claimed design.
